FEEDING MECHANISM FOR ROCK DRILLS

John C. Curtis, Garfield Heights, Ohio, assignor
to The Cleveland Rock Drill Company, Cleve-
land, Ohio, a corporation of Ohio

Application April 21, 1936, Serial No. 75,593

7 Claims. (Cl. 255—45)

This invention relates broadly to rock drills, but more particularly to a feeding mechanism for rock drills of the percussive type.

One object of this invention is to produce a feeding mechanism for rock drills susceptible of manual and automatic operation for imparting feeding motion to the drill.

Another object of this invention is to provide a feeding mechanism for rock drills with means readily operable for selectively transforming the feeding mechanism in a manually or automatically operated mechanism.

Another object of this invention is to provide a normally automatically operated feeding device for rock drills with means shaped and disposed in the most common manner whereby manual feeding motion may be imparted to the drill irrespective of said mechanism.

Other objects and advantages more or less ancillary to the foregoing and the manner in which the various objects are attained, reside in the specific construction and aggroupment of the elements peculiar to this structure, as will become apparent from a more complete examination of this specification, in the claims of which there are assembled certain specific combinations of parts and specific constructions indicative of the scope and spirit of the invention.

In the drawings:

Fig. 1 is a longitudinal view partly in section illustrating a rock drill having the improved feeding mechanism applied thereto, the rock drill being shown positioned at one extreme end of its travel.

Fig. 2 is a view similar to Fig. 1 illustrating the rock drill in another position.

Fig. 3 is an enlarged longitudinal sectional view of the connection between the drill and the feeding mechanism.

Fig. 4 is an enlarged cross sectional view taken in a plane indicated by line 4—4 in Fig. 1.

Fig. 5 is an enlarged cross sectional view taken in a plane indicated by line 5—5 in Fig. 1.

Fig. 6 is a view similar to Fig. 5 illustrating some of the parts in different position.

Fig. 7 is an enlarged sectional view taken in a plane indicated by line 7—7 in Fig. 5.

Fig. 8 is a sectional view taken in a plane indicated by line 8—8 in Fig. 5.

Fig. 9 is a side elevational view of the part shown in Fig. 8.

Figs. 10, 11 and 12 are cross sectional views taken in a plane indicated by line 10—10 in Fig. 5 and looking in the direction of the arrows terminating the line. For purpose of illustration,

the handle located at the extreme left end of Fig. 5 has been shown in dotted lines in these three figures.

Fig. 13 is a longitudinal sectional view taken in a plane indicated by line 13—13 in Fig. 5 illustrating the left end portion of the mechanism shown in Fig. 1.

Fig. 14 is an enlarged cross sectional view taken in a plane indicated by line 14—14 in Fig. 2.

Fig. 15 is an enlarged sectional view taken in a plane indicated by line 15—15 in Fig. 10.

Referring to the drawings in which like symbols designate corresponding parts throughout the several views, 16 represents a percussive rock drill or drilling motor having a piston (not shown) 15 reciprocable therein for imparting blows to a drill steel 17 reciprocably mounted within the front housing of the rock drill. The motive fluid may be admitted into the motor 16 through a connection 18 forming a part of the back head 19. 20

The lower wall of the motor 16 extends laterally to form two longitudinally disposed guides 20, which are slidably guided within the corresponding guideways 21 formed with the upper portion of a tube or shell 22. This shell is located under 25 the motor 16 to support the same, and has its lower portion also formed with guides 23 slidably guided within the guideways 24 of a stationary support 25. For mounting purpose, this support has a conical portion 26 depending therefrom. 30 The length of the support 25 is substantially equal to one half the length of the shell 22, which is slidable relatively thereto with the motor 16 slid-
able on the shell.

Located within the right end of the shell 22 in 35 Fig. 1, hereinafter denoted as the front end of the mechanism, there is a sprocket wheel 27 rotatably mounted on a shaft or bolt 28 transversely disposed through the shell 22. The position of this shaft is such that the sprocket wheel 27 protrudes 40 below the shell through a short slot 29 provided in the bottom of the shell.

Mounted within the rear end of the shell 22, there is a housing 30 secured therein by bolts 31 extending through the housing and shell. Trans- 45 versely disposed within the housing 30, there is a shaft 32 which is formed with an integral handle 33 extending outside of the housing for rotary movement within a vertical plane located on the left hand side of the assembly when viewed from 50 the left end in Fig. 1. Disposed through the shaft 32 adjacent the handle 33, there is a cross pin 34 of a length substantially equal to the bore 35 of a cover or cap 36 secured to the side of the housing 30 by bolts 37. Clamped between the cap 36 and 55

the adjacent side wall of the housing 30, there is the partly annular shoulder 33 of a sleeve 39. The side wall of the sleeve 39 is partly machined to form two diametrically opposed substantially V-shaped cams 40 with the bottom thereof arcuated as at 41 to accommodate the pin 34, while the top ends thereof are recessed as at 42 to form stops and locks for the pin 34.

Journaled on the shaft 32, there is a sleeve 43 which extends beyond the inner end of the shaft. This sleeve has its right end portion in Fig. 5 slotted to slidably receive the cross pin 44 of a short shaft 45, which is slidably mounted within the sleeve 43 in abutting engagement with the shaft 32. The cross pin 44 carries a clutch member 46 slidably mounted on the sleeve 43, and formed with splines 47. This clutch member is constantly urged toward the left in Fig. 5 by the effort of a compression spring 48, which is seated on a washer 49, the latter being secured to the sleeve 43 by a spring clip 50.

The splines 47 of the clutch member 46 are capable of operative engagement with the corresponding splines 51 of a worm gear 52, which is rotatably mounted within the housing 30. Meshing with the teeth of the worm gear 52, there is a worm 53 disposed longitudinally within the housing 30 and rotatable by a crank handle 54, which is secured thereto by a bolt 55.

Intermediate its ends, the sleeve 43 has secured thereon by a key 56, a sprocket wheel 57, which is located between two spacers 58 and 59, the former having the worm wheel 52 rotatably mounted thereon. The housing 30 has an arcuated wall 60 extending behind the sprocket wheel 57 as shown in Fig. 13, while ahead of the sprocket wheel the housing is provided with two substantially rectangular openings 61 and 62, the purpose of which will be explained later.

Adjacent the cap 36, there is secured on the sleeve 43 by a key 63 a disk 64, which has its peripheral wall formed with teeth 65. Pivotally mounted within the wall of the housing 30 adjacent the peripheral wall of the disk 64, there are two sets of pawls 66 and 67. In the present construction, there are shown six pawls 66, which are located with respect to the teeth 65 for alternative operative engagement with one side thereof, and two pawls 67 capable of alternative engagement with the other side of the teeth 65. Each of these pawls has a torsion spring 68 associated therewith for constantly urging the pawls in engagement with the teeth 65 of the disk 64. The pawls 66 and 67 are somewhat longer than the width of the disk 64, and extend beyond the latter over a cam plate 69, which is rotatably mounted between the disk 64 and the cover 36. The normal outside diameter of this plate is substantially equal to or somewhat greater than the outside diameter of the disk 64, and has a hub like portion 70 rotatably mounted within the sleeve 39. This hub 70 is also slotted to receive the cross pin 34 by which the rotation of the shaft 32 is transmitted to the cam plate 69, while the sleeve 39 is locked against rotation to the cover 36 by a small lock pin 71. The peripheral wall of the cam plate 69 is formed with two diametrically opposed cut away portions or notches 72 of a sufficient length for accommodating the pawls 66.

Depending from the drilling motor 16 into the shell 22, there is a longitudinally apertured lug 73 having a sleeve 74 extending therethrough and formed with a collar 75 engaging one side of the lug. The collar has a flat portion 76 engaging the lower wall of the motor 16 to lock the

sleeve against rotation relative to the lug. The other end of the sleeve 74 is threaded to receive a nut 77 engaging the other side of the lug. Within the sleeve 74, there is a longitudinally disposed pin 78 having a nut 79 secured to the inner end thereof, and engaging a rubber buffer 80 located between the nuts 77 and 79. The pin 78 extends through the nut 77 where it is fastened thereto by a cross pin 81, to the end of a chain 82. From the apertured lug, the chain 82 extends rearwardly through the rectangular opening 61 formed within the housing 30, where it passes over the sprocket wheel 57, and therefrom it extends forwardly toward the support 25, through the rectangular opening 62. The other end of the chain is finally secured to the rear end of the support 25 by a bolt 83, which is adjustable longitudinally by nuts 84 within an apertured lug 25 depending from the support 25.

Secured by a cross pin 86 to the sleeve 74 mounted within the apertured lug 73 of the motor 16, there is the end of another chain 87, which chain extends forwardly over the sprocket wheel 27 mounted within the front end of the shell 22. From the sprocket wheel 27, the chain 87 extends rearwardly toward the support 25, where its other end is affixed to the front end of the support by a cross pin 88.

From the foregoing, it will be noticed that the portion of the chains 82 and 87 extending from the drilling motor lug 73 to their respective sprocket wheel, is located inside of the shell 22, while the portion thereof extending from the sprocket wheels to the support 25, is located under the shell 22.

In the operation of the mechanism, let us assume that the handle or lever 33 of the shaft 32 is positioned as shown by dotted lines in Fig. 10. In this instance, the cross pin 34 of the shaft 32 is engaging the bottom 41 of the cam 40, thus permitting the short shaft 45 to assume the position shown in Fig. 5 and thereby causing the engagement of the clutch member 46 with the corresponding splines 51 of the worm gear 52. Due to the effort of the compression spring 48 on the clutch member 46, the short shaft 45 is constantly urged toward the left in Fig. 5, thus exerting pressure on the end of the shaft 32 for maintaining its cross pin 34 in forcible engagement with the cam 40. When the parts are positioned as shown in Fig. 5, it will be understood that the sprocket wheel 57 is normally locked against rotation due to the interengagement of gear 52 and worm 53, preventing thereby the accidental slideable movement of the motor 16 relative to the shell 22 and support 25. It will also be understood that manual rotation may be imparted to the worm gear 52 by the worm 53 and crank handle 54, which rotation is transmitted to the sleeve 43 by the cross pin 44. From the sleeve 43 the rotation is transmitted to the sprocket wheel 57 through the key 56, and to the disk 64 through the key 63. In this instance, the plate 69 which is connected to the momentarily stationary shaft 32 by the cross pin 34 is held in the position shown in Fig. 10. In this position the normal peripheral wall of the disk engages the end of the pawls 66 and 67 which protrudes from the disk 64, thus preventing the engagement of the pawls with the teeth 65 of the disk, and thereby permitting the free rotation of the sprocket wheel 57 which is manually imparted thereto by rotating the crank handle 54. Since the sprocket wheels 27 and 57 are carried by the shell 22, and that the chains passing over these sprocket wheels have one end

affixed to the support and the other end to the motor, it will be understood that the rotation of the sprocket wheel 57 will cause the longitudinal movement of the shell and motor relative to the support, the drilling motor moving in the same direction as the drill but at a double rate of speed, its possible range of travel being equal to the combined range of travel of the motor on the shell and of the shell on the support.

When it is desired to change the feeding mechanism from a manual to an automatic operation, it is only necessary to shift the lever or handle 33 in either the position shown in Fig. 11 or Fig. 12. During the rotation of the handle 33 from the position shown in Fig. 10 to the one shown in Fig. 11 for instance, the cross pin 34 engaging the cam 40 will move from the bottom 41 into the recesses 42, thus causing the longitudinal movement of the shaft 32 and the consequential slideable movement toward the right in Fig. 5, of the short shaft 45. The cross pin 34, carried by the short shaft 45, will cause the clutch member 46 to move out of engagement with the worm gear 52 as shown in Fig. 6. When the handle 33 is positioned as shown in dotted line in Fig. 11, the plate 69 being rotated by the cross pin 34 will also be positioned as shown in this last figure, that is with the notches 72 in opposition to the pawls 66, thus permitting the operative engagement of the pawls with the teeth 65 of the disk 64.

During the operation of the drilling motor 16, the reversal of the piston strokes therein will impart jars or forward and rearward movement to the motor 15, thus normally imparting oscillatory motion to the sprocket wheel 57. When the plate 69 is positioned as shown in Fig. 11, the pawls 66 engaging one side of the teeth 65, will prevent the rotation of the disk 64, sleeve 43 and sprocket wheel 57 in a clockwise direction in Fig. 11, thus preventing the rearward movement of the motor 16. During the forward movement of the motor, the sprocket wheel 57 and disk 64 will rotate in a counterclockwise direction in Fig. 11, which rotation is not checked by the pawls 66 since the latter will simply ride the teeth 65 without interference. From the foregoing, it will be understood that when the handle 33 is positioned as shown in Fig. 11, the drilling motor 16, due to the jars imparted thereto, is capable of step by step forward movement, while the rearward movement thereof is prevented by the engagement of the pawls 66 with the teeth of the disk 64.

When it is desired to feed the motor rearwardly, the handle 33 may be rotated in the position shown in dotted line in Fig. 12. In this instance, the cross pin 34 riding the cam 40 will again be positioned within two of the recesses 42, thus again causing the disengagement of the clutch member 46 with the worm gear 52 as shown in Fig. 6. The plate 69 being driven by the cross pin 34 will assume the position shown in Fig. 12 to permit the engagement of the pawls 67 with the teeth 65 of the ring 64 and prevent the engagement of the pawls 66. In this instance, the rotation of the disk 64 and sprocket wheel 57 in a counterclockwise direction in Fig. 12 is prevented by the engagement of the pawls 67 with the teeth 65, thus preventing the forward movement of the motor 16. During the rearward movement of the motor, the sprocket wheel 57 and disk 64 will rotate in a clockwise direction in Fig. 12, which rotation is not checked by the pawls 67 since the latter will simply ride the teeth of the disk 64 without interference, thus permitting a step by step rearward movement of the motor.

When it is desired to manually feed the motor 16 toward or away from the work, the handle 33 may simply be positioned as shown in Fig. 10, thus causing the reengagement of the clutch member 46 with the worm gear 52 as shown in Fig. 5, and positioning the plate 69 as shown in Fig. 10 to maintain the pawls 66 and 67 out of engagement with the teeth 65 of the disk 69.

When the feeding mechanism is automatically operated, it will be understood that the shell 22 and motor 16 are fed toward or away from the work in the manner specified in connection with the manual operation of the mechanism, the motor moving in the same direction as the shell but at a double rate of speed.

During the operation of the drilling motor 16, the jars of the latter transmitted to the chain 82 which passes over the sprocket wheel 57, will be greatly cushioned by the rubber buffer 80 mounted within the apertured lug 73, thus protecting the chain against sudden jars which may cause the breakage thereof, as well as eliminating excessive vibrations in the mechanism associated with the sprocket wheel 57.

Although the foregoing description is necessarily of a detailed character, in order to completely set forth the invention, it is to be understood that various rearrangements of parts and modification of structural detail may be resorted to without departing from the scope or spirit of the invention as herein claimed.

I claim:

1. In a drilling apparatus, the combination with a stationary support, of a shell slideable thereon, of a drilling motor slideable on said shell having jars imparted thereto, a mechanism associated with said motor and shell for imparting slideable movement thereto, means manually operated connectable with said mechanism for actuating the same, means automatically operated by the jars of said motor connectable with said mechanism for actuating the same, and means for selectively connecting said manually or automatically operated means with said mechanism.

2. In a drilling apparatus, the combination with a stationary support, of a shell slideable thereon, of a drilling motor slideable on said shell having jars imparted thereto, a mechanism associated with said motor and shell for imparting slideable movement thereto, said mechanism being normally automatically operated by the jars of said motor, manually operable means connectable with said mechanism for actuating the same independently of said jars, and means for connecting said manually operable means with said mechanism and simultaneously rendering the automatic operation thereof ineffective.

3. In a drilling apparatus, the combination with a stationary support, a shell slideable thereon, a drilling motor slideable on said shell having jars imparted thereto, a sprocket wheel carried by said shell meshing with a chain connected to said support and motor, a jar resisting mechanism and a manually operable rotation mechanism connectable with said sprocket wheel for either causing a step by step slideable movement of said motor and shell due to the jars of said motor or for imparting continuous slideable movement to said motor and shell, and means for selectively connecting either of said mechanisms to said sprocket wheel.

4. In a drilling apparatus, the combination with a stationary support, a shell slideable thereon, a drilling motor slideable on said shell having jars imparted thereto, a mechanism associated with said motor and shell including movement trans-

- mitting means for transmitting continuous slide-
able movement to said motor and shell and move-
ment checking means for checking the jars of said
motor in one direction and thereby causing a step
5 by step slideable movement of said motor and
shell in the other direction, and means for se-
lectively and operatively connecting said move-
ment transmitting or checking means with said
mechanism.
- 10 5. In a drilling apparatus, the combination with
a support, of a shell slideable thereon, of a drilling
motor slideable on said shell, of a feeding mecha-
nism associated with said motor and shell for
effecting the slideable movement of said motor at
15 a faster rate of speed than that of said shell,
manually operable means and means auto-
matically operable by the jars of said motor con-
nectable with said mechanism for actuating the
same, and means for selectively connecting said
20 manually operable or said automatically operable
means with said mechanism.

6. In a drilling apparatus, the combination with
a support, of a shell slideable thereon, of a drilling
motor slideable on said shell, of a feeding mecha-
nism associated with said motor and shell for
25 effecting the slideable movement thereof at a

greater rate of speed for said motor than for
said shell, manually operated means and power
operated means connectable with said feeding
mechanism for actuating the same, and unitary
means for selectively connecting either of said
5 operated means with said mechanism.

7. In a drilling apparatus, the combination with
a support, of a shell slideable on the support, of a
motor slideable on the shell having a piston re-
ciprocable therein imparting jars thereto tending
10 to move the motor back and forth relative to the
support, means utilizing the jars of the motor
for effecting a step by step movement thereof in
one direction including a sprocket wheel rotat-
ably mounted on the shell near each end there-
of, a chain meshing with said wheels and con-
nected to the support and motor for movement
with the latter normally resulting in the os-
cillatory movement of the wheels, and a mecha-
nism carried by the shell including stop means
20 associated with one of said wheels for selectively
controlling the direction of rotation thereof to
enable a step by step movement of said chain and
consequently of said motor in one or the other
direction.

JOHN C. CURTIS.
